UNITED STATES PATENT OFFICE.

AUGUST W. DONOP, OF SAN FRANCISCO, CALIFORNIA, ASSIGNOR TO U. S. LIGHT & HEAT CORPORATION, OF NIAGARA FALLS, NEW YORK, A CORPORATION OF NEW YORK.

COMPRESSIBLE-PILE REGULATOR.

1,417,151.

Specification of Letters Patent. Patented May 23, 1922.

Application filed March 26, 1919. Serial No. 285,383.

To all whom it may concern:

Be it known that I, AUGUST W. DONOP, a citizen of the United States, residing at 1086 Post St., San Francisco, in the county of 5 San Francisco and State of California, have invented new and useful Improvements in Compressible-Pile Regulators, of which the following is a specification.

The present invention relates to compressible pile regulators.

More particularly the present invention relates to regulators wherein the pressure exerted upon the compressible pile is varied to vary the resistance of said pile. In many 15 devices of this nature, difficulty has been encountered for the reason that the discs of which such piles are commonly made up, do not loosen as desired when pressure is released.

20 An object of the present invention is to provide a compressible pile with operating means therefor in which the plates will be loosened when pressure is released.

25 A further object is to provide a construction which is sturdy and cheap to manufacture.

Other objects will be apparent as the description proceeds.

The one figure of the drawing represents a 30 sectional view illustrating one embodiment of the present invention. Briefly stated, the invention comprises a series of conducting plates of compressible material such as carbon, which are mounted in contact with one 35 another upon a rod having frictional engagement with said plates. Means are provided for tightly compressing said plates when it is desired to reduce the resistance of the compressible pile to a minimum. The 40 rod, by frictional engagement with the several plates of the pile, loosens said plates from one another.

The compressible pile is indicated by the 45 numeral 1, said pile being made up of a number of plates 2, 2. Each one of the plates 2, 2 is preferably provided with a perforation 3. The discs are mounted upon a rod 4 which extends through the perforations. As illustrated in the drawings, the 50 perforations 3, 3 are larger than the rod 4 in order to provide for inequalities in manufacture, and in order that the discs 2, 2 may ride loosely on the rod 4. Securely mounted upon the rod 4 is a thrust plate 5. This

thrust plate 5 may be held by the nut 6 55 which has engagement with a screw-threaded portion 7 on the rod 4. Said thrust plate 5 is adapted to exert pressure upon one end of the pile 1.

A pair of supporting members 8, 9 are 60 provided which serve to support the rod 4 and also to support a magnetic core 10 upon which is mounted a solenoid 11. Pivotedly supported by the supporting member 9 is a lever 12 pivoted at the point 13. One end 65 of said lever 12 is provided with an armature 14, while the other end 15 of said lever 12 is adapted to contact with one end of the rod 4. The screw-threaded end 7 of the rod 4 may be provided with a bushing 16 to provide a bearing whereby said rod 4 may slide 70 freely. The other end of the rod 4 has a bearing in the supporting member 8. A spring 17 may be provided for biasing the lever 12 to urge the rod 4 toward the left as 75 viewed in the drawing, whereby the thrust plate 5 will compact the compressible pile 1.

A mode of operation of the above-described embodiment of the invention is substantially as follows: The solenoid 11 may be connected to any circuit to the functions of which it should respond. The compressible pile 1 may be connected in the circuits whose resistance it is desired to vary. Action of the spring 17 will tend to compact the pile 1 85 to reduce the resistance of same to a minimum. Energization of the solenoid 11 will result in an attraction of armature 14. When said solenoid 11 has been energized to a predetermined extent, its attraction will 90 result in the movement of lever 12 in a clockwise direction, thereby relieving pressure on the compressible pile 1. The plates, being relieved from a state of compression, will move the thrust plate 5 toward the right 95 as viewed in the drawing, which in turn will move the rod 4 toward the right. The rod 4, on account of its frictional engagement with the several plates of the pile, will loosen said plates from one another, whereby there will 100 be a uniform increase in the resistance of the pile throughout its length.

The contour of the plates 2, 2 and of the rod 4 may be varied as desired. Many other modifications may be made. It is intended in this patent to cover all such modifications that fall within the scope of the invention as defined by the appended claims.

What I claim as new and desire to secure by Letters Patent of the United States is—

1. In a compressible pile, a plurality of plates and operating means for said pile having frictional engagement with each of said plates.

2. In a compressible pile, a plurality of

plates, means for communicating pressure to compact said plates and means engaging each of said plates to loosen said plates when pressure is released.

In witness whereof, I have hereunto subscribed my name.

AUGUST W. DONOP.
